UNITED STATES PATENT OFFICE.

CHARLES W. TIMMONS, OF LAPEL, INDIANA.

ELECTRIC LAMP.

Application filed July 18, 1924. Serial No. 726,862.

To all whom it may concern:

Be it known that I, CHARLES W. TIMMONS, a citizen of the United States, residing at Lapel, in the county of Madison and 5 State of Indiana, have invented certain new and useful Improvements in Electric Lamps, of which the following is a specification.

My invention relates to portable electric lamps.

10 An important object of the invention is to provide an electric lamp of the above mentioned character, having a dynamo as a source of current, which is operated by a spring motor, the several parts being arranged in a compact manner, whereby the lamp may be used as the ordinary flash light.

Other objects and advantages of the invention will be apparent during the course 20 of the following description.

In the accompanying drawings forming a part of this specification, and in which like numerals are employed to designate like parts throughout the same,

25 Figure 1 is a horizontal section through the lamp, taken on line 1—1 of Figure 2,

Figure 2 is a transverse section taken on line 2—2 of Figure 1,

Figure 3 is a transverse section taken on 30 line 3—3 of Figure 1, and,

Figure 4 is a side elevation of a modified form of the invention, parts in central vertical section.

In the drawings, wherein for the purpose 35 of illustration are shown preferred embodiments of my invention, attention being called first to Figures 1 to 3 inclusive, the numeral 5 designates a preferably cylindrical casing, within the forward portion of

40 which is mounted a stationary armature 6, of a generator of any well known or preferred type. This generator embodies the usual armature having an armature shaft 7. The armature is equipped with the usual

45 commutator 8, and terminals or brushes 9 and 10, engage with this commutator. These brushes are rigidly mounted upon and insulated from a transverse bar 11, carried by the casing 5. The brush 10 is grounded

50 to the casing 5, by means of a wire 12. The spring contact 13 is mounted upon the bar 11, and insulated therefrom, but is in electrical connection with the brush 9.

55 The numeral 14 designates a reflector, disposed rearwardly of a lens 15, held in place

by a ring 16, having screw threaded engagement with the casing 5. This reflector is preferably formed of polished metal, and is in electrical connection with the casing 5. The reflector 14 carries a socket 17, for 60 receiving the stud of an electric bulb 18, of the usual construction. The outer terminal of the stud of this bulb is in electrical connection with the reflector 14, while the inner terminal 19, engages the spring 13. 65

The electrical generator is driven by means of a spring motor, which will now be described.

The numeral 20 designates a rotatable handle or wheel, having a reduced end 21, 70 rotatable within the rear end of the casing 5.

This reduced end is provided with an annular groove 22, the bottom wall of which has ratchet teeth 23, which are faced in a direction to permit the handle 20 being 75 turned clock-wise. These ratchet teeth are engaged by a resilient dog or pawl 24, attached to the rear end of the casing 5, as shown at 25. A screw 26 is carried by the rear end of the casing 5, and extends into 80 the annular groove 22. This screw and also the pawl 24, effect a swiveled connection between the handle 20 and the rear end of the casing, whereby this handle may turn upon the casing but cannot partake of perceptible longitudinal movement thereon. 85

Extending centrally and longitudinally within the rear end of the casing 5 is a rotatable shaft 27, having its rear end portion journaled in a bearing 28, formed in 90 a vertical or radial arm 29, rigidly attached within the casing 5. The extreme rear end of this shaft is also journaled within a bearing 30, formed upon the inner face of the handle or wheel 20. The extreme forward 95 end of the shaft 27 is rotatable within a sleeve 31, in turn rotatable within a bearing 32, formed in a radial arm 33, rigidly attached to the interior of the casing 5. The arm 29 carries an arm extension 34, 100 rigidly attached thereto and this arm extension carries a stud 35, upon which is rotatably mounted an intermediate gear 36. This intermediate gear engages at its outer portion with an internal annular gear 37, 105 and at its inner portion with an inner smaller gear 38, rigidly mounted upon the rear end of the shaft 27. It is seen that when the handle 20 is turned, this motion will be transmitted to the intermediate gear 36, 110

which will turn the inner gear 38 at an increased speed.

- The numeral 39 designates a torsional coil spring, surrounding the shaft 27, and having its inner end fixed thereto, as indicated at 40. The outer end of this spring is looped for connection with a pin 41, which is attached to the outer edge of a radial disk 42, rotatable upon the shaft 27. 10 This radial disk carries a pin 43, near its center, which engages within the looped inner end of a torsional coil spring 44, surrounding the shaft 27. The outer end of this spring 24 is looped for receiving a pin 15 45, secured to the outer edge of a radial disk 46, rotatable upon the shaft 27. This disk 46 carries near its center a pin 47, inserted within the looped inner end 48 of a torsional coil spring 49, surrounding the shaft 20 27. This spring 49 has its outer end looped for receiving a pin 50, attached to the outer portion of a radial disk 51. This radial disk is rigidly mounted upon the rear end 30 of the sleeve 31, to turn the same. 25 The sleeve 31 has a crown gear 52 rigidly mounted upon its rear end, for rotation therewith. This crown gear has its annular set of gear teeth 53 arranged to engage with a gear 54, rotatable upon a radial shaft 55, 35 which is journaled in the sides of the casing 5. The shaft 55 carries a large gear 56, rigidly secured thereto, and this large gear engages a smaller gear 57, rigidly mounted upon a rotatable shaft 58, journaled in the sides of the casing 5. This 40 smaller gear drives a larger gear 59, rotatable therewith and this larger gear drives a smaller gear 60, rigid upon a shaft 61, journaled in the sides of the casing 5. This 45 smaller gear drives a larger beveled gear 62, rotatable therewith, and this beveled gear drives a smaller beveled gear 63, which is rigidly mounted upon the rear end of the armature shaft 7, which is journaled through a radial bearing 64.

I provide automatic means to maintain constant the speed of the armature shaft, and for the purpose of illustration I have shown a fan governor 65, rigidly mounted 50 thereon. The invention is in no sense restricted to this particular type of speed governor, as a centrifugal governor or any other form of governor may be employed. The fan governor is adapted to be engaged 55 and disengaged by a catch 66, carried by a slide 67, operating in a guide 68.

In the operation of this form of the device, the motor may be held against action, by moving the slide 67 forwardly until the 60 catch engages the fan 65. The spring motor may be wound by turning the handle 20, clock-wise. When the fan is released, the spring motor serves to drive the sun gear 52, and this in turn drives a train of gears, 65 rotating the armature shaft 70. The genera-

tor is then set in action and current generated, which is supplied to the bulb 18.

In Figure 4, I have shown a second or modified form of my invention, in the embodiment of a lantern. This lantern embodies a base 70, having an upwardly extending internal annular flange 71, within which is rotatable a winding element or wheel 72. This winding wheel is held against a flange 73, by means of a ring 74, having screw threaded engagement with the flange 71, as indicated at 75. The winding wheel is turned by thumb pieces 76. This winding wheel is provided upon its lower face with an annular set of ratchet teeth 77, 80 engaged by a spring dog 78, which permits the winding wheel to turn in one direction only.

The numeral 79 designates a base casing, 85 detachably secured to the base 70, and having a top 80, provided with a central bearing 81, receiving a vertical shaft 82, the lower portion of which is journaled in a bearing 83 and a collar 84 is rigidly secured thereto, to prevent vertical displacement of the shaft. The shaft 82 carries at its lower end a gear 84, rigidly attached thereto, engaging an outer intermediate gear 85, rotatable upon a stationary stud 86. This intermediate gear 85 engages an annular internal gear 87, formed upon the inner face of the top of the winding wheel 72. It is thus seen that when the winding wheel is turned, the intermediate gear 85 will transmit the rotation to the shaft 82.

Arranged within the casing 79 is a torsional coil spring 88, the inner end of which is fixed to the shaft 82, at 89, and the outer end of this spring is looped to receive a pin 90, carried by a horizontal crown gear 91, which is rotatable upon the shaft 82, above a stop collar 92, fixed thereon. This crown gear embodies an upper annular set of internal gear teeth 93, engaging a smaller gear 94, rigidly mounted upon a vertical shaft 95, journaled in bearings 96, fixed to the top 80. The shaft 95 has a large gear 97 rigidly mounted thereon, engaging a smaller gear 98, driving a larger gear 99. This larger gear engages a smaller gear 100, driving a larger gear 101. This larger gear 101 engages and drives a smaller gear 102, rigidly mounted upon the lower end of an armature shaft 103. This armature shaft is journaled at its lower end through a bearing 104. At the top, the armature shaft 103 has a stop collar 105, and is journaled in a bearing 106, carried by a stationary bar 107. This armature shaft is carried by the usual armature, operating within a stationary field winding 108, held within a vertical casing 109, carrying a base flange 110, screwed upon the top of the base casing 79. The armature is provided with the usual commutator 111, engaged by brushes 112 and 113. The brush 130

113 is grounded to the vertical casing 109 by a wire 114; while the brush 112 is mounted upon the bar 107, with the brush 113, and both of these brushes are insulated from this bar.

A resilient contact 115 is mounted upon the bar 107 and is in electrical connection with the brush 112. The contact 115 engages the inner electrode 116 of an electric 10 bulb 117, the outer electrode of which is in electrical connection with a socket 118, carried by a supporting element 119, attached to a shade support 120, and hence in electrical connection with the vertical casing or 15 ground 109. The shade support carries a shade 121 of any well known or preferred type.

Means are provided to maintain the speed of the armature shaft 103, constant, during 20 operation, and for this purpose I provide the same with a fan governor 122, rigidly mounted thereon, operating within the vertical casing 109. This fan governor is adapted to be engaged and disengaged by a catch 25 123, carried by a slide 124, operating within a guide 125.

In view of the foregoing description, it will be seen that when the catch 123 is in the lower position, it will engage the fan governor 122, and the generator will be held against operation. When the winding wheel has been turned sufficiently to wind the spring 88, to a proper tension, the catch 123 may be elevated to release the fan governor 35 122, and the generator will be set in motion, and supply current to the bulb 117.

It is to be understood that the forms of my invention herewith shown and described, are to be taken as preferred examples of the 40 same, and that various changes in the shape, size, and arrangement of parts, may be resorted to, without departing from the spirit of my invention, or the scope of the subjoined claims.

45 Having thus described my invention, I claim:

1. An electric lamp comprising a casing, a generator arranged in the forward end thereof and including an armature shaft, 50 a bulb carried by the casing in advance of the generator and electrically connected therewith, a spring motor arranged in the rear portion of the casing, a crown gear rotatable within the casing adjacent to the 55 spring motor and driven thereby, a plurality of transverse shafts arranged between the crown gear and motor, a gear mounted upon the rear transverse shaft and engaging the crown gear, a longitudinal train of gears 60 mounted within the casing between the

crown gear and generator and carried by the transverse shafts and serving to connect said gear and armature shaft of the generator, a rotatable fan-governor rigidly mounted upon the armature shaft near the generator, and a latch slidable upon the outer surface of the casing and having a part movable into and out of engagement with the fan-governor, a rotatable winding wheel mounted upon the rear end of the casing, pawl and 65 ratchet means preventing back turning of the winding wheel, and speed increasing gearing between the winding wheel and the spring motor.

2. An electric lamp comprising an elongated casing, a generator arranged in the forward end of the casing and including an armature shaft, a bulb carried by the forward end of the casing in advance of the generator and electrically connected therewith, a spring motor arranged in the rear portion of the casing, a crown gear rotatable within the casing in advance of the spring motor and connected with and driven by the spring motor, a plurality of transverse shafts 80 having their ends journaled in bearings carried by the casing and arranged between the crown gear and generator, a gear mounted upon the rear transverse shaft and engaging the crown gear, a longitudinal train of gears 85 mounted within the casing between the crown gear and generator and carried by the transverse shafts and serving to connect said gear and the armature shaft of the generator, a rotatable fan-governor rigidly mounted 90 upon the said armature shaft, a catch slidable upon the casing and having a part movable into and out of engagement with the fan-governor, and manually operated means to place the spring motor under tension.

3. An electric lamp comprising a casing, a generator arranged in the forward end of the casing and including an armature shaft, a bulb carried by the casing and electrically connected with the generator, a spring motor arranged within the casing, a crown gear driven by the spring motor, speed increasing gearing between the crown and the armature shaft of the generator, a fan-governor 105 connected with the armature shaft, a catch 110 movably mounted upon the casing and adapted to engage and disengage the fan-governor, a rotatable winding wheel carried by the casing, pawl and ratchet means preventing back turning of the winding wheel, and speed increasing gearing between the winding wheel and the spring motor.

In testimony whereof I affix my signature.

CHARLES W. TIMMONS.
